JP	05115535	5/1993

Primary Examiner—Ian Simmons*(74) Attorney, Agent, or Firm*—Ohlandt, Greeley, Ruggiero & Perle, LLP(57) **CLAIM**

The ornamental design for a bottle, as shown and described.

DESCRIPTION

FIG. 1 is a perspective view of a bottle showing our new design;

FIG. 2 is a front view of the bottle of FIG. 1;

FIG. 3 is a rear view of the bottle of FIG. 1;

FIG. 4 is a side view of the bottle of FIG. 1, the opposite side being a mirror image thereof;

FIG. 5 is a top view of the bottle of FIG. 1;

FIG. 6 is a bottom view of the bottle of FIG. 1;

FIG. 7 is a perspective view of a second embodiment of a bottle, showing our new design;

FIG. 8 is a front view thereof;

FIG. 9 is a rear view thereof;

FIG. 10 is a side view thereof, the opposite side being a mirror image thereof;

FIG. 11 is a top view thereof; and,

FIG. 12 is a bottom view thereof.

The broken line showing in FIGS. 1 through 12 is for illustrative purposes only and forms no part of the claimed design.

1 Claim, 8 Drawing Sheets
